UNITED STATES PATENT OFFICE.

PAUL ANDRÉ CAMILLE DUWOOS, OF ROUEN, FRANCE.

TYPOGRAPHICAL PRINTING MACHINE.

Application filed August 5, 1926, Serial No. 127,456, and in France August 8, 1925.

My present invention relates to typographical printing machines and it has for its object to provide a platen printing machine of this type, characterized by a continuously moving inking device which is completely independent from the chase or form carrying platen.

Said inking device comprises paste contacting rollers carried by a roller chain unit 10 formerly moved around the platen, said contacting rollers being charged with ink as they are moved over a suitably arranged bed plate and then inking the form secured beneath the platen.

15 The platen is completely independent from the inking device, which is carried by the frame of the machine. In order to allow the contact rollers to ink the form, the platen will be stopped at the top of its stroke for a time necessary for the passage of the rollers. This result will be obtained by actuating the platen by means of a particular mechanism having two connecting rods.

In the accompanying drawings:

25 Fig. 1 is a front elevation of the complete machine.

Fig. 2 is a corresponding side elevation.

Fig. 3 is a longitudinal section of the upper part of the machine, showing the inking 30 mechanism.

Fig. 4 is one half of the transverse section of the same part.

The two last views have been simplified to facilitate comprehension thereof.

35 Fig. 5 is a detail view of the ratchet mechanism.

Fig. 6 is a detail view of the connection between the roller and cam mechanism.

In the present arrangement of the machine, the platen A carries the form B at its lower part. Said form may be either a form with movable types or better a typographical block. The same is slidably arranged in guide-ways C in the frame and actuated by two connecting-rods D and E, to which movements are imparted by a crank-disc F and a cam G respectively and the upper ends of which are pivotally connected to the ends of a pivoted or fulcrumed cross-bar H, pivoted 45 around the pin I on the platen. The disc F and cam G are rotated in opposite directions, the one with half the speed of the other, and their respective radii are determined so as to impart to the platen reciprocating movement with a slackening equivalent to a stop-

ping during about one quarter of the period near the upper dead centre.

The printing will be effected on a stationary slab J, where a movable hand-guard K supports the usual parts.

60 The form or block B will be inked prior to each printing by one of the two sets of contact-rollers L—L. Said sets each comprise two rollers covered with typographical paste, the axis of which is journaled in particular links M inserted into the roller chains N. Said chains will be moved uniformly in the direction of the arrow I, and such movement is combined with the movement of the platen in such a way that the rollers will be 65 passed over the block or form as the same is stopped. During this inking period the rollers will be held in contact with the block or form by rails Q urged by adjustable tension springs and the contact with the block or form will be adjusted by contact-guides R on which rest the pulleys of the rollers. Said rails Q and R are carried by the platen and 70 secure to the path of the contact or inking rollers an invariable position with relation to the block or form during the whole period of inking.

75 The chains N will be moved by the sprocket wheels O loosely arranged on a shaft V and each of which is made integral with a pinion U meshing with a pinion T keyed on a shaft S. In order to have a perfect synchronism of movement for both chains the guide pinions P are keyed on the same shaft X.

80 The contact rollers will be charged with 90 ink as they pass over a cylindrical table Y keyed on the shaft V and receiving a uniform movement in a direction opposite to that of the chains. Such movement will be imparted to it by the shaft S and the set of 95 pinions a, b, c.

An ink pot with a yielding blade d is arranged in the machine between the chains, the feed-roller e is actuated thereby through the agency of a ratchet and a lever f actuated 100 by a cam g formed at one end of the table Y.

A take-off roller h carried by two levers keyed on an axle i will be reciprocated between the ink-pot and table by a cam j formed on the opposite end of the table. Said 105 roller covered with paste will be charged with ink as it comes into contact with the feed roller and it will deposit such ink upon the table.

The ink deposited in this way will be 110

brought owing to the rotation of the table on an equalizing roller *k* covered with paste. Said roller which is freely held by two levers keyed on the shaft *l* and resting on the distributing roller *m*, will be moved with the rotating table which will impart a rotary movement to the roller *m* around its axis *l*. The roller *m* will moreover reciprocate parallel to its axis by the action of a conventional device with two screws having crossing threads.

Thus the ink will be suitably distributed and equalized on the entire width of the table before the freshly inked zone will come into contact with the contact rollers. A lever *n* attached to the end of the shaft *l* enables the pressure of the roller *k* on the table to be easily adjusted.

Thus the complete inking mechanism is entirely independent from the platen and merely supported by the frame members of the machine. The same will be actuated from a single shaft *S* actuated in turn by a silent chain with central guide *Z* actuated by the crank-disk *F*.

In the printing machine thus constructed the only important reciprocating parts are the platen and connecting rods; the weight thereof may be reduced to a minimum compatible with the conditions of resistance and thus high speeds may be obtained without excessive strain on the parts.

The continuous movement of the contact rollers is also favourable to obtain such high speed, at the same time securing perfect inking in spite of the very high speed at the passage over the form.

The machine will be suitable for printing on spooled paper and card with the addition of an apparatus intended to feed the latter after each printing. The same may be particularly coupled with a machine working such printed strip of paper and manufacturing labels, boxes and other similar articles. The machine may also be provided with a device enabling sheets of paper to be printed with automatic margining.

I wish it to be understood that I have merely described an example of the improved mechanism. Particularly the platen may receive different movements nonparallel, and particularly adapted to be opened like a portfolio; the same may be arranged below the stone and carry the block or form at its upper part in order to effect printing on the back side of the paper; the ink-pot, take-off, equalizing and distributing rollers as well as the inking table may be arranged in different ways, the number of said parts may be varied as well as that of the contact rollers, without

departing from the scope and spirit of the invention.

Having now fully described my said invention, what I claim and desire to secure by Letters Patent, is:

1. In a platen typographical printing machine, the combination with the general printing mechanism, of an inking device, comprising paste contact rollers, a chain carrying said rollers, means for imparting a uniform rotary movement around the platen of the machine to the same, a suitably arranged inking table over which said rollers are moved to be charged with ink, and a form secured below the platen intended to be inked by said rollers, and means for actuating the platen of the machine comprising two connecting-rods, a crank-disc and a cam-disc actuating said connecting rods, a cross-bar pivoting around a pin on the platen, said connecting rods being pivotally connected to the ends of said cross-bar, substantially as set forth.

2. In a platen typographical machine, printing mechanism including a reciprocating platen, an inking device including an endless carrier, inking rollers carried by said carrier, a rotatable inking table over which the rollers are moved to be charged with ink, means for rotating the inking table in a direction opposed to the movement of said endless carrier, means for reciprocating the platen, said means being arranged to interrupt the normal platen movement at its upper limit whereby to permit the inking rollers to contact with the platen carried form during such interrupted platen movement, and means carried on the platen to maintain a fixed contact of the rollers with relation to the form during the travel of the rollers over the form.

3. In a platen typographical printing machine, general printing mechanism including a platen, means for reciprocating the platen arranged to provide a dwell in the movement of the platen at its upper position, a chain carrier mounted for travel transverse the platen, inking rollers carried by the chain carrier and movable in a plane below the platen in their operative relation to the platen, a cylindrical inking table to supply ink to said rollers, means for supplying ink to the table, means for operating the table in opposition to the movement of the chain carrier, and guides on the platen cooperating with the axes of the printing rollers while moving across the platen to maintain a fixed path of travel of said rollers.

In testimony whereof I have hereunto set my hand.

PAUL ANDRÉ CAMILLE DUWOOS.
